PROCESS FOR THE RECOVERY
OF PHENOLS

Henry G. Berger, Edwin M. Nygaard, and Henry S. Angel, Woodbury, N. J., assignors to Socony-Vacuum Oil Company, Incorporated, New York, N. Y., a corporation of New York

No Drawing. Application December 2, 1941,
Serial No. 421,328

3 Claims. (CL. 260—627)

This invention has to do with an improved process for the recovery of phenols from petroleum oils. More specifically, the present invention relates to an improved process for the recovery of phenols from caustic liquors containing phenolates, naphthenates and mercaptides derived from caustic treatment of petroleum fractions.

As is well known to those familiar with the art, crude petroleum oils and distillate fractions obtained therefrom contain constituents other than compounds consisting only of carbon and hydrogen. Among these are compounds containing sulphur, nitrogen, oxygen, etc. Generally such oxygen compounds are represented by phenols, naphthenic acids, etc., and such sulphur compounds by mercaptans, thiophenes, disulphides, etc. Various methods are employed to extract these compounds from the petroleum fractions and methods have been proposed for recovery of the phenols so removed from the mixture in which they are extracted. Usually, phenols, naphthenic acids and mercaptans are removed from petroleum fractions containing these compounds by treatment with strong aqueous or alcoholic caustic solution. Such treatment converts phenols to phenolates, naphthenic acids to naphthenates, and mercaptans to mercaptides. Then the caustic solution containing phenolates, naphthenates and mercaptides is separated from the oil. The caustic solution is then oxidized with H_2O_2 , Cl_2 , O_2 , etc., to convert mercaptides to disulphides, which are insoluble in the caustic solution and separate as an oil, which is withdrawn from the mixture. This procedure is unsatisfactory, however, for part of the phenols are destroyed by degradational oxidation; the undestroyed phenols remain in solution as alkali metal phenolates in combination with the alkali metal salts of the naphthenic acids; and some disulphides remain occluded in the caustic solution. Thus, the processes proposed in the prior art do not provide for the complete removal of the sulphur compounds, and do not provide for the production of substantially pure phenols.

We have discovered a process which involves a novel sequence of operations for the recovery of phenols from the caustic wash liquors obtained in the caustic treatment of petroleum fractions. By this process, phenols substantially free of naphthenic acids and sulphur are obtained. The process contemplated by this invention comprises the following operations: admixing the caustic wash liquor from a caustic-treated petroleum fraction with an amount of sulphur sufficient

to convert the mercaptides to disulphides and with a water-immiscible organic solvent for disulphides; agitating this mixture and separating the caustic layer containing the phenolates and naphthenates from the organic solvent layer containing the disulphides, carbonating the caustic layer to convert the phenolates to phenols, and separating the carbonated caustic solution containing the naphthenates from the phenols. To effect 10 a more rapid and complete separation of the carbonated caustic solution containing the naphthenates from the phenols, we contemplate the modification of adding a water-immiscible organic solvent for phenols to the carbonated caustic layer, separating the carbonated caustic solution containing the naphthenates from the solvent layer containing the phenols and evaporating said solvent from the phenols. After these 15 operations, the phenols are substantially free of naphthenic acids and sulphur, and may be further purified by steam distillation.

We also contemplate the recovery of phenols by means of the foregoing process from acidified caustic liquors of petroleum fractions containing 20 phenols, naphthenic acids and mercaptans. To convert the acid solution containing phenols, naphthenic acids, mercaptans and oil to a caustic solution corresponding to the original caustic solution in the aforesaid process, the following steps 25 are taken: distilling with steam or vacuum the acid solution containing phenols, naphthenic acids, mercaptans and oil to as low a residue as possible, discarding the residue, extracting the distillate with a water-immiscible organic solvent 30 and extracting the solvent with a 5-10% caustic solution, separating the phases by withdrawing the caustic layer from the organic solvent layer containing neutral oil and organic residuum, discarding the organic solvent layer, 35 and treating the caustic layer according to the sequence of operations first hereinabove described.

The petroleum fractions from which the caustic liquors are obtained may be any petroleum fractions containing phenols, naphthenic acids and mercaptans which when caustic treated and separated from the caustic solution will be substantially free of the aforesaid classes of compounds, said compounds now being present in the caustic solution in the form of phenolates, naphthenates and mercaptides. In general, caustic liquors recovered from the caustic treatment or caustic washing of thermally or catalytically cracked petroleum distillates will serve the purposes of our invention.

The term "caustic liquor" used herein describes a liquor obtained by treatment of a petroleum fraction with an alkali hydroxide, as for example, NaOH, KOH, etc. For the purposes of economy and efficiency of operation, we have found NaOH most useful. And as aforesaid, we also contemplate the utilization of acidified caustic liquors as coming within the scope of this invention. When an acidified caustic liquor is used, it has been found that desired results are obtained when a slight excess of alkali hydroxide is used over the amount required to combine with the acidic components in the solvent layer.

Suitable solvents are those designated as "water-immiscible organic solvents." Such solvents as benzene, ether, chloroform, carbon tetrachloride, etc., and low-boiling petroleum distillates, as for example, petroleum ether are preferred.

To demonstrate the invention, the following typical example is given:

EXAMPLE

An acidified spent caustic wash liquor containing a crude mixture of phenols, naphthenic acids and sulphur compounds, and represented by data given in Tables 1 and 2, was treated as described below:

TABLE 1

Specific gravity	1.0306
Per cent H ₂ O by volume	7.3
Per cent sulphur	2.72
Per cent phenol	10.2
Per cent tar acids as phenol	43.6
N. N.	141

TABLE 2

Distillation	°F.	°C.
5%	222	106
50	398	203
90	470	243
Dry	476	247
Tar in flask	2	-----
per cent		

306 grams of the crude material were steam distilled, the temperature of the distilling liquid being about 130° C. The distillate was extracted with petroleum ether and the aqueous layer extracted again with fresh petroleum ether to remove from it the bulk of the residual organic material. The combined petroleum ether extracts were now agitated with 350 cc. of 10% sodium hydroxide. This amount of sodium hydroxide represents a slight excess over the amount required to combine with the acidic components in the petroleum ether layer. The caustic and petroleum ether layers were separated. The residue obtained by evaporating the solvent from the petroleum ether layer amounted to seven grams and was discarded; this represents neutral oil.

The sodium hydroxide layer was agitated vigorously with 600 cc. of a petroleum ether solution saturated with sulphur until a small portion of the petroleum ether layer indicates complete conversion of the sodium mercaptides to disulfides. This is evidenced by a negative doctor test by which —S—H— and —S—M groups, wherein M is a metal, as, for example, Na, are shown to be absent from the solution. The sodium hydroxide and petroleum ether layers are now separated. Removal of petroleum ether from this extract yields organic disulfides.

The sodium hydroxide layer was now carbonated with carbon dioxide. The carbonation

causes a separation of the phenols from the aqueous layer containing sodium naphthenates. The phenolic layer may be separated from the aqueous layer, or for a more complete separation the mixture is extracted with a water-immiscible organic solvent. For example, this carbonated mixture was extracted with 150 cc. of petroleum ether. The petroleum ether layer containing the phenols was separated and the petroleum ether evaporated, leaving the phenols as a residue. If desired, the phenols may be further purified by steam distillation.

The aqueous sodium carbonate layer was acidified with hydrochloric acid. This causes a separation of the free naphthenic acids which can be drawn off or can be further purified by distillation.

Results of this example are summarized in Table 3 given below:

20

TABLE 3
Summary of data on products obtained after processing original material

Product	Grams isolated	Per cent of total	Per cent sulphur	Per cent of total sulphur
Neutral oil	5.0	1.6	-----	11.72
Sulphur compounds	23.0	7.5	22.9	0.49
Naphthenic acids	21.5	7.1	0.7	0.066
Phenols	100.5	33.0	0.2	0.066
Residue	62.0	20.3	4.1	0.63
Represented by				
Loss water content	22.0	7.2	-----	
By manipulation	72.0	23.5	-----	

35 ¹ Includes an excess of elementary sulphur used in the conversion of sodium mercaptides to disulfides.

Thus, the efficacy of our process is demonstrated by the sulphur content of the purified phenols as compared with the over-all sulphur content of the original material. As shown in Table 1, the sulphur content of the original material is 2.72%, and in Table 3, the sulphur content of the purified phenols is only 0.2%.

It is to be understood that the foregoing specific example is for illustrative purposes only and that various modifications may be made therein by those skilled in the art without departing from the scope of the appended claims.

We claim:

- 50 1. The process for the recovery of phenols from aqueous caustic liquors containing phenolates, naphthenates and mercaptides derived from a crude caustic-treated petroleum fraction from which neutral oils have been removed, comprising
55 the following sequence of operations: admixing said aqueous caustic liquor with a water-immiscible organic solvent for disulfides and an amount of sulphur sufficient to convert said mercaptides to disulfides; agitating this mixture and separating the aqueous caustic layer containing the phenolates and naphthenates from the organic solvent layer containing the disulfides; carbonating said aqueous caustic layer to convert the phenolates to phenols and aiding the separation
60 of the phases by adding a water-immiscible organic solvent for phenols; separating the carbonated caustic solution containing the naphthenates from the solvent layer containing the phenols; and evaporating said solvent from the phenols.

- 65 2. The process for the recovery of phenols from aqueous caustic liquors containing phenolates, naphthenates and mercaptides derived from a crude caustic-treated petroleum fraction from which neutral oils have been removed, compris-

70

ing the following sequence of operations: admixing said aqueous caustic liquor with a water-immiscible organic solvent for disulfides and an amount of sulphur sufficient to convert said mercaptides to disulfides; agitating this mixture and separating the aqueous caustic layer containing the phenolates and naphthenates from the organic solvent layer containing the disulfides; carbonating the caustic layer to convert said aqueous phenolates to phenols and aiding the separation of the two phases by adding a water-immiscible organic solvent for phenols; separating the carbonated aqueous caustic solution containing the naphthenates from the solvent layer containing the phenols; evaporating said solvent from the phenols; and purifying the phenols by steam distillation.

3. The process for the recovery of phenols from aqueous caustic liquors containing phenolates, naphthenates and mercaptides derived from a crude caustic-treated cracked petroleum distil-

late from which neutral oils have been removed, comprising the following sequence of operations: admixing said aqueous caustic liquor with petroleum ether to dissolve disulfides and an amount of sulphur sufficient to convert said mercaptides to disulfides, agitating this mixture and separating the aqueous caustic layer containing the phenolates and naphthenates from the petroleum ether layer containing the disulfides; carbonating said aqueous caustic layer to convert the phenolates to phenols and aiding the separation of the two phases by adding petroleum ether to dissolve phenols; separating the carbonated aqueous solution containing the naphthenates from the petroleum ether layer containing the phenols; evaporating petroleum ether from the phenols; and purifying the phenols by steam distillation.

CERTIFICATE OF CORRECTION.

Patent No. 2,342,386.

February 22, 1944.

HENRY G. BERGER, ET AL.

It is hereby certified that error appears in the printed specification of the above numbered patent requiring correction as follows: Page 3, first column, line 8-9, claim 2, for "carbonating the caustic layer to convert said aqueous" read --carbonating said aqueous caustic layer to convert the--; and that the said Letters Patent should be read with this correction therein that the same may conform to the record of the case in the Patent Office.

Signed and sealed this 9th day of May, A. D. 1944.
